UNITED STATES PATENT OFFICE.

HIRAM A. FRANTZ, OF CHERRYVILLE, PENNSYLVANIA.

EXPLOSIVE-ENGINE.

No. 830,144.

Specification of Letters Patent.

Patented Sept. 4, 1906.

Application filed February 21, 1905. Serial No. 248,652.

To all whom it may concern:

Be it known that I, HIRAM A. FRANTZ, a citizen of the United States, residing in Cherryville, Northampton county, Pennsylvania, have invented certain new and useful Improvements in Explosive-Engines, of which the following is a specification.

My invention relates to that class of explosive-engines in which a liquid fuel, such as kerosene, is employed, and more particularly to an improved fuel-charging mechanism for such engines adapted to operate in connection with separate reservoirs for storing, respectively, the regular charging fuel and a more volatile fuel, such as gasolene, which is used mainly to facilitate starting of the engine.

The invention is fully described in connection with the accompanying drawings, and the novel features are specifically pointed out in the claims.

Figure 1 is a sectional elevation showing an explosive-engine of ordinary construction in the main, having my improvements applied thereto in preferred form. Fig. 2 is an elevation, partly in section and to an enlarged scale, taken at right angles to Fig. 1 and showing particularly the pump and feed-pipe connections thereto from the reservoirs.

The engine-cylinder 1 and crank-chamber 2 are mounted, as usual, on a base 3, which latter is chambered to serve as an oil-reservoir. The piston 4 has its rod 5 connected to the crank 6 of the shaft 7, which latter is mounted in suitable bearings 8 and provided with fly-wheels 9. The cylinder 1 and cylinder-head 10 are water-jacketed, as usual, the water-inlet being represented at 11 and the outlet at 12, while 13 indicates the exhaust outlet from said cylinder, and 14 the air-inlet thereto communicating through a wall-conduit 15 with the crank-chamber 2. Air is admitted to the latter through the valve-controlled inlet 16 during the upward stroke of the piston and is compressed during the downward stroke until the inlet-port 14 to the cylinder is opened, as indicated in the Fig. 1 position.

The pump-barrel 17, with its packing-head 18, is carried by an open frame 19, secured to fixed brackets 20 and 21 and provided at its upper end with a shaft-sleeve 22. The pump-plunger 23 has an enlarged upward extension 24, guided vertically in cross-bars 25 26 of the frame 19 and provided at its upper end with a roller 27, mounted, as shown, upon a trans-

verse pin 28. A spring 29 is arranged to normally raise the plunger to a regulated height determined by an adjustable stop-lever 30, Fig. 2, pivoted to the frame 19 at 31, as shown, and locked in adjusted position by an engaging quadrant 32. The roller end of the plunger extension is located below the engine-shaft 7 adjacent to a cam-sleeve 33, feathered on said shaft and slidable thereon by the action of governor-arms 34 34, as indicated. The cam portion 35 of this rotating sleeve is adapted to contact with the roller 27 below it when the cam-sleeve is in operating position upon the shaft, so as to depress the plunger at each revolution of the cam-sleeve; but whenever the sleeve is moved outward by the governor so as to clear the roller the pump action is automatically intermittent until the sleeve is returned to operating position by the reduction in speed of the engine. The edges 36 and 37 of the cam and roller, respectively, are beveled, as shown, so as to provide for their proper engagement or disengagement, as the case may be, when the cam-sleeve is in an intermediate position on the shaft.

As previously stated, the chambered base 3 is adapted to serve for storing the liquid fuel (kerosene) intended to be employed during the ordinary operation of the engine. A separate reservoir 38 for gasolene is suitably supported adjacent to the reservoir 3. The feed-outlet 38^a from the latter is connected by suitable piping to the bottom head 39 of the pump and the gasolene-reservoir is connected intermediately at 40 to said piping, suitable valve mechanism 41 and 42 being provided to cut off communication of either of the reservoirs, as desired, with the pump. The liquid fuel from either communicating reservoir is conveyed to the pump-barrel, as shown, through a screen 43 and duplicate ball-valves 44 44 at each upward movement of the plunger, the amount so conveyed being determined by the extent of the said plunger movement, as determined by the adjustable stop 30. Connected also to the bottom pump-head 39 by a fitting 45, provided, as shown, with duplicate ball-valves 46 46, is the feed-pipe 47, extending therefrom to the engine-cylinder. At a point in said pipe or conduit 47 in line with the cylinder-inlet 14 I provide a suitable valve mechanism, comprising a body 48, engaging said inlet-opening and having a reduced nozzle 49 in the latter through which the liquid fuel may be discharged into said cylinder-inlet in connec-

tion with the air-supply to the latter through the air-conduit 15, already referred to. This fuel-inlet is controlled by a plunger-valve 50, adapted to cut off the same when in the position indicated in Fig. 1, and provided with a passage-way 51, aligned when in such position with the conduit-pipe 47, so as to permit the free passage of the fuel liquid to the extended conduit 47^a, said plunger-valve being also adapted when withdrawn from its seat to cut off such free passage thereby and open communication through its hollow end portion and the nozzle 49 into the cylinder-inlet 14.

The extended conduit-pipe 47^a is carried upward and connected to a fitting 52, having a vertical bracket portion 53 tightly entered in the fuel-inlet 54, formed in the cylinder-head 10. Suitable valves 55, 56, and 57 are provided, as shown, in the fitting 52 and branches thereof, adapted to be opened by the pump-pressure and permit passage of the fuel liquid to said inlet, the valves 56 and 57 being provided with springs adapted to normally seat them. In order to conveniently determine whether or not the fuel liquid is being properly delivered, I provide a hand-valve 58 in the fitting 52, the withdrawal of which from its seat permits said fuel to discharge through a visible outlet 59.

The operation has been clearly indicated in connection with the detailed description already given. In starting the engine the kerosene-reservoir 3 is cut off, as described, from the pump and the gasolene is fed to the latter and discharged through inlet 14 into the engine-cylinder together with air from the crank-chamber, the valve 50 being properly set, as stated, while during the normal succeeding operation of the engine the kerosene-reservoir is put into communication with the pump, the gasolene-reservoir is cut off, the valve 50 is set to cut off the inlet 14, and the kerosene is fed, as determined by the governor action and the adjustable stroke of the pump, to the top inlet 54 and the vaporizer-plate 60 below the same, the air-supply continuing as before through the lower inlet 14. It will of course be understood that the terms "gasolene" and "kerosene" are em-

ployed broadly, as indicating liquid fuels of 50 relatively high and low volatility, respectively and also that the preferred mechanism specifically described may be readily modified without departing from the invention.

55

What I claim is—

1. In a gas-engine a charging mechanism comprising separate reservoirs for gasolene and kerosene, a common pump with feed-pipes to and from the same, cut-off means for 60 said reservoirs, separate inlets to the engine-cylinder arranged in communication with the common feed-pipe thereto, and cut-off means for said inlets, substantially as set forth.

2. In a gas-engine a charging mechanism 65 comprising separate reservoirs for gasolene and kerosene, a common pump with feed-pipes to and from the same, cut-off means for said reservoirs, separate inlets to the engine-cylinder arranged in communication with the 70 common feed-pipe thereto, cut-off means for said inlets, and a separate air-conduit to one of said inlets substantially as set forth.

3. In a gas-engine a charging mechanism 75 comprising separate reservoirs for gasolene and kerosene, a common pump with feed-pipes to and from the same, cut-off means for said reservoirs, separate inlets to the engine-cylinder arranged in communication with the common feed-pipe thereto, a separate air-conduit to one of said inlets, and a valve mechanism controlling the pump-discharge into the latter, substantially as set forth.

4. In a gas-engine a charging mechanism 80 comprising a pump for the charging liquid, a top inlet to the engine-cylinder for said charging liquid, a vaporizer-plate below said inlet, a nozzle in said inlet with conduit connections to the pump, and valves in said conduit adapted to be opened by the pump-pressure, substantially as set forth.

In testimony whereof I affix my signature in the presence of two witnesses.

HIRAM A. FRANTZ.
